Primary Examiner — Susan Moon Lee(74) *Attorney, Agent, or Firm* — Patent Law Offices of Rick Martin, P.C.(57) **CLAIM**

The ornamental design for a webbing dog harness, as shown and described.

DESCRIPTION

FIG. 1 is a top perspective view of my new design for a webbing dog harness;

FIG. 2 is a top plan section view of my new design for a webbing dog harness;

FIG. 3 is a top plan section view, a continuation from FIG. 1, of my new design for a webbing dog harness;

FIG. 4 is a rear elevation section view of my new design for a webbing dog harness;

FIG. 5 is a rear elevation section view, a continuation from FIG. 4, of my new design for a webbing dog harness;

FIG. 6 is a front elevation section view, of my new design for a webbing dog harness;

FIG. 7 is a front elevation section view, a continuation from FIG. 6, of my new design for a webbing dog harness;

FIG. 8 is a bottom plan section view of my new design for a webbing dog harness;

FIG. 9 is a bottom plan section view, a continuation from FIG. 8, of my new design for a webbing dog harness; and,

FIG. 10 is a right side elevation view of my new design for a webbing dog harness, the left side elevation view being a mirror image thereof.

The broken line elements are not claimed.
